ISIDORE PANES

BY *M. M. Co.*

ATTORNEYS

UNITED STATES PATENT OFFICE.

ISIDORE PANES, OF NEW YORK, N. Y.

BRASSIÈRE.

1,379,416.

Specification of Letters Patent. Patented May 24, 1921.

Application filed August 3, 1920. Serial No. 400,946.

To all whom it may concern:

Be it known that I, ISIDORE PANES, a citizen of the United States, and resident of the city of New York, borough of the Bronx, in 5 the county of Bronx and State of New York, have invented a new and useful Brassière, of which the following is a full, clear, and exact description.

This invention relates to clothing and particularly to an improved brassière, and has 10 for an object to provide an improved construction wherein the garment may be easily put on and taken off.

Another object in view is to provide a 15 form of brassière in which it is divided at one point and formed with a securing means for connecting the point or division together adjacent the side.

A further object of the invention is to 20 provide a brassière which is formed of two independent parts connected together at the upper edge with each part provided with tie strings for independently tying the front and back sections in place.

25 An additional object is to provide a brassière in which there is arranged a body structure and an adjustable suspender structure.

The invention contemplates the provision 30 of brassières for women of different sizes and may be readily caused to properly fit a comparatively small person, but is especially designed for large persons, or women having large breasts. In carrying out the inventive idea the parts are so arranged that 35 each part may be independently tied in position, especially the front part, and the tying means are arranged to draw in the breast and also the stomach to a comparatively neat figure before the tying action.

In the accompanying drawing:

Figure 1 discloses a figure provided with a brassière designed for a rather slender person.

45 Fig. 2 is a rear view of the figure and brassière shown in Fig. 1.

Fig. 3 is a view of a comparatively stout figure with a brassière partially applied thereto.

50 Fig. 4 is a plan view of a brassière embodying the invention spread out, the same being on a slightly reduced scale.

Fig. 5 is a perspective view showing the lower part of one of the suspenders and 55 illustrating how the suspenders are adjustably connected to the brassière body.

Fig. 6 is a vertical sectional view through Fig. 5 approximately on line 6—6.

Fig. 7 is a perspective view similar to Fig. 5 but disclosing a modified form of the 60 invention.

Referring to the accompanying drawing by numerals, 1 indicates the front section of the brassière and 2 the rear section. Shoulder straps 3 and 4 are stitched or 65 otherwise rigidly secured to the rear section 2, and are removably connected with the front section 1 as shown particularly in Figs. 5 and 6. The shoulder straps may be made in any desired manner, but preferably 70 of at least two ply, especially at the front one ply or strip could be provided with eyes or other fastening means and the other ply or strip could be provided with a hook. Preferably a number of eyes 6 are arranged 75 on strip 5 and only one hook 8 on strip 7, though others could be provided without departing from the spirit of the invention.

A link 9 is connected with the front section by a suitable connecting strip 10 80 stitched to the front section. The strip 5 is threaded through the link 9 and bent upon itself as shown in Fig. 5 so that any one of the eyes 6 may receive the hook 8. By having a series of these eyes the length of the 85 respective straps 3 and 4 may be varied to suit the person using the device. If desired the extreme end of the strip 5 could be cut off and the unnecessary eyes 6 removed thereby.

In Fig. 7 will be seen a slightly modified form of this adjustable connection of the shoulder straps in which a buckle 11 of ordinary construction is substituted for the hook and eyes.

The rear section 2 is made to substantially conform to a figure of a given size and tie strings or cords 12 and 13 connected to the lower edge adjacent each end, said cords being adapted to be passed around the body 100 and tied in front. It will be noted also that the section 2 is provided with gore members 14 and 15 at the ends, which act in a certain sense as overlapping flaps. These gore members or flaps co-act with gore members 105 or flaps 16 and 17 arranged on the ends of section 1. The sections 1 and 2 are connected together at point 18 by one or more lines of stitching passing through the upper end of the respective flaps 14 and 17. This 110 provides a positive connection along the upper edge of the brassière and allows the

lower edge to be drawn in around the waist line and to overlap to any desired extent. Arranged on section 1 is a tape or other strip 19 on which hooks 20 are mounted 5 adapted to co-act with the eyes 21 arranged on the tape or strip 22 stitched or otherwise rigidly secured to the section 2 at the end opposite point 18.

When the brassière is first put on it may 10 be arranged as shown in Fig. 3 and then the hooks interlocked with the eyes 21 or else the eyes and hooks could be positioned at the front until interlocked and then the entire garment slid around to the correct position 15 after which the front and back sections could be correctly positioned and tied down by the tie strings 12 and 13 and also the tie strings 23 and 24. After the brassière has been placed in position and before the tie 20 strings have been used the shoulder straps 3 and 4 are properly adjusted and then the front section 1 is pulled down by the tab 25. In adjusting the front section 1 the shoulder straps 3 and 4 are first properly adjusted to 25 the proper length and then the strings 23 and 24 pulled toward the back and preferably crossed so that they may be tied in front as shown in Fig. 1. This pull from the lower corner of the flaps 16 and 17 draws 30 in the bust to the desired extent and also assists in drawing in the stomach. It will be noted that both the rear and front sections produce a pressure or tension on the body of the person using the device and this 35 binding or tension is caused by the various tying strings particularly, though the supporting of the upper part of the garment assists the strings in securing the desired results.

40 What I claim is:

1. A brassière comprising a body, means connecting the lower part of the body to a person, and a pair of adjustable suspenders for supporting the upper part of the body,

each of said suspenders having at one end a 45 pair of strips, a link adapted to be pivotally connected with said body through which one of said strips is adapted to be passed, said last mentioned strip being looped back upon itself, a plurality of eyelets arranged on said 50 looped back portion, and a hook secured to the other of said strips, said hook being adapted to interlock with any of said eyelets according to the length of shoulder strap desired. 55

2. A brassière comprising a body formed in two parts connected together substantially end to end, releasable connecting means at the ends of said part opposite the point of connection, and a plurality of tie 60 members connected to the lower part of the body for tying said lower part in place.

3. A brassière comprising a front section, a rear section, said sections at one end being connected together by stitching adjacent the 65 upper edge, adjustable releasable locking members at the respective ends of said sections, and means secured to the lower part of each section for bringing said section under tension for causing the respective sections to snugly fit the person wearing the 70 garment. 75

4. A brassière comprising a front section, a rear section, said sections being connected together end to end at a point adjacent the upper edge, each of said sections being formed with overlapping flaps at each end and means connected to each end of each section for drawing the sections tightly 80 against the person using the device and causing said flaps to overlap, a series of hooks and eyes connected to said sections at the respective ends of said sections adjacent their upper edges, said hooks and eyes connecting the free ends of said sections together. 85
